C. F. WHORF.

Cooking Stove.

No. 40,527.

Patented Nov. 3, 1863.

Attest,
Edward Lillman
A. J. Willard.

Inventor.
Charles F. Whorf
By his Atty
Amos Woodard.

UNITED STATES PATENT OFFICE.

CHARLES F. WHORF, OF ST. LOUIS, MISSOURI.

IMPROVEMENT IN COOKING-STOVES.

Specification forming part of Letters Patent No. 40,527, dated November 3, 1863.

To all whom it may concern:

Be it known that I, CHARLES F. WHORF, of the city and county of St. Louis, and State of Missouri, have invented a new and useful Cooking Apparatus; and I do hereby declare the following to be a full, clear, and exact description of the same, reference being had to the annexed drawings, making part of this specification, in which—

Figure 1 is a front elevation of my said apparatus; Fig. 2, a vertical section on the line A'; Fig. 3, a horizontal section on the line B'; and Fig. 4 a plan of one of the ovens.

The object of my invention is to provide a more complete and efficient cooking apparatus or stove. To realize this object I have constructed the following described apparatus, which I have found by experience to fulfil the end sought after—viz., to bake, broil, roast, and boil, all at one time and with one stove or single furnace. The lower portion of this apparatus is represented in the drawings by A. It is rectangular in form, and comprises the roasting-ovens, the furnace, and the broiling-pan and grate.

B represents the furnace, lined with loose plates d d, or not, as circumstances may require.

a is the grate of said furnace, fitted on a pivot in the center, that it may be shook to and fro by a lever (not shown in the drawings) to clear the furnace of ashes. The furnace-door is shown by h.

C O are the roasting-ovens, of which there are four disposed all around the furnace, and the doors whereof are shown by E, Fig. 3, and a plan of which is shown by Fig. 4, and which, it will be seen, are made angular, so as to reflect and concentrate the heat toward the center thereof.

C is the grate upon which the thing to be roasted is placed. This grate may be made to set horizontally, as at e, or it may be made to incline toward the back part of the oven, as at e', so as to give the thing roasted the full benefit of the heat radiated from the top and side plates of the oven, which are the hottest, being nearest the furnace. A revolving spit may also be used in these ovens, if it should be desired. I make the apparatus with both spits and grates.

e e are openings in the back of the ovens, through which the roasting fumes escape, and

i i are holes in the top of the oven-doors, to cause a draft through the ovens and ash-pit. By keeping the ash-pit door shut the draft for the furnace will be made to pass through the oven, by which means different things may be cooked in the ovens at the same time without tasting of each other.

D is a pan fitted in a receptacle made on the under side of the stove to receive it, and which serves the double purpose of ash-pan and broiling-pan. Whenever it may be desired to broil anything the ashes are dumped out of said pan and a charcoal-fire is made therein under the gridiron, upon which the broiling is done, the fumes passing up through the furnace-grate.

The boiler, making part of this apparatus, is represented in the drawings by E. It consists of a rectangularly-shaped tank or reservoir, arranged all around the three sides of the upper part of the main furnace, either in one boiler or in three separate ones. In the furnace B there are three coils of pipes, G, placed to communicate with the said reservoir, from which the water has free circulation into said pipes, whereby the water is heated. In the top of said reservoirs a series of boiler or pot holes, H, are made, through which the bottoms of said pots or boilers are let down into the water and boiled. These reservoirs should be provided with cocks to draw off the water whenever it may be desirable. The coils of pipes here referred to are shown in Fig. 3 in dotted lines.

The bake-oven is shown in the drawings by I. It is rectangular in form, and is constructed in a cylinder, R, placed over the furnace, as shown, so as to leave a vertical flue, J, on three sides thereof, the front side being occupied by the oven-door L. The plate M forms at once the lower end of the cylinder, the bottom plate of the bake-oven, and the top plate of the furnace. By these means the oven is very rapidly and evenly heated. There should be a hole, as at f, made near the top of the cylinder to clean the dirt off of the top of the oven.

N represents a canopy, through which the draft-pipe K passes, and in which pipes are set to carry off any steam or heat that may be generated about the apparatus when in operation.

g g are resting-pieces made in the sides of the oven to set bake-pans, &c., on.

The different plates comprising the appa-

ratus are put together by any of the well-known means by which stove-plates are now united.

The loose plates d in the furnace are to prevent the furnace-plates from burning out, and also to modify the heat of the ovens.

The furnace B, it will be seen, expands at the top, the object of which is to diffuse the heat and to keep the pipes out of the intense heat of the fire, so as to save them from burning out.

Having now described the construction and

operation of my invention, what I claim, and desire to secure by Letters Patent, is—

The combination of the ovens C C and I and water-tank E with the furnace B, when constructed substantially as described, and forming the substantial parts of a cooking apparatus, as set forth.

CHARLES F. WHORF.
